UNITED STATES PATENT OFFICE.

DON J. HIGGINBOTHAM, OF RIALTO, FLORIDA.

STAMPING DEVICE.

1,078,854.

Specification of Letters Patent. Patented Nov. 18, 1913.

Application filed January 2, 1913. Serial No. 739,784.

To all whom it may concern:

Be it known that I, DON J. HIGGINBOTHAM, citizen of the United States, residing at Rialto, in the county of Lee and State of Florida, have invented certain new and useful Improvements in Stamping Devices, of which the following is a specification.

This invention relates to improvements in stamping devices employed for stamping or printing an impression upon various articles, but designed more particularly for use in stamping characters upon boxes or other closures, and has for one of its objects to provide a simply constructed device whereby a plurality of stamps or printing faces are connected to a single body and adapted to be employed one at a time and independently so that a variety of different marks or characters will be applied successfully to a series of boxes or other closures by simply turning the device until the desired characters are in position to be impressed upon the closure.

Another object of the invention is to provide a simply constructed device whereby the different character impressing devices may be detachably connected and readily changeable when desired or to enable the marks to be renewed when impaired or worn out.

Another object of the invention is to provide a simply constructed device whereby the character or mark is associated with other characters or marks denoting its value or quality.

With these and other objects in view the invention consists in certain novel features of construction as hereinafter shown and described and then specifically pointed out in the claims, and in the drawings illustrative of the preferred embodiment of the invention, Figure 1 is a top plan view partly in section of the improved device. Fig. 2 is a side elevation, partly in section.

Corresponding and like parts are referred to in the following description and indicated in all the views of the drawings by the same reference characters.

The improved device comprises a body, represented as a whole at 10, and preferably constructed of a block of wood with a plurality of relatively long flat faces around the edge, and a plurality of relatively short flat faces connecting the longer flat faces.

Any required number of the flat faces may be employed, but generally eight of each size

will be used, as illustrated. The longer flat faces are represented at 11 and the connecting flat faces at 12. The upper face of the block or body 10 is flat, as shown in Fig. 1, 60 while the lower face is formed with a relatively small flat face 13 and with a plurality of obliquely extending faces indicated at 14 connecting the faces 13 with the adjacent margin of the body. By this means when 65 the body is located in a vertical position, as shown in Fig. 2, the projecting face 13 provides a bearing to support the flat side portions 11-12 spaced above the supporting structure. The annular faces 14 are utilized to contain characters denoting the quality of the goods or other information, as hereafter explained.

Extending over the flat faces 11-12 from the upper flat face of the block or body is 75 an encompassing rib 15, while a similar rib 16 extends laterally from the body or block at the lower sides of the flat faces. By this means the body or block is entirely encompassed by the ribs and forms the flat faces 80 into a continuous channel-like conformation. The ribs 15-16 opposite the smaller flat faces 12 are of less width than the portions of the ribs opposite the longer flat faces 11, as shown.

The channel-like conformation of the block or body is designed to receive a continuous strip of flexible material, such as relatively hard rubber 17 upon the outer face of which suitable characters are formed in raised figures, as represented at 18, and form the printing surfaces of the stamp device. The portion of the strip 17 which comes opposite to the longer flat faces 11 are thicker than the portions of the strip which come opposite to the shorter flat surfaces 16, as shown. The thicker portions of the strip correspond substantially to the width of the portions of the ribs 15-16 which are located opposite to the longer flat faces, leaving the 100 printing characters 18 projecting beyond all of the faces of the body. The thicker portions of the strip 17 which come opposite to the shorter flat faces 12 are designed to receive clamp plates 19, which are secured in 105 place by screws or other fastening devices 20 and operate through the clamp plates and the thinner portions of the strip 17 and into the body or block 10. By this simple means the strip of flexible material, which contains 110 the printing characters, is firmly supported in position upon the block or body and leav-

ing the printing characters projecting beyond all of the faces of the body.

A suitable handle 21 is connected to the body centrally of its flat side as shown.

5 The inclined faces 14 are provided with characters denoting the quality of the goods to be stamped, and any suitable characters may be employed, but for the purpose of illustration the characters denoting the quality of oranges, grape fruit, and the like, are shown for the purpose of illustration and the words Fancy, Bright, Golden and Russet are employed and the characters 96, 100 and 28 are shown upon the longer thicker portions 10 of the flexible strip, which are in view in Fig. 2, the characters denoting the number of oranges or grape fruit which are deposited in the closure to be stamped. Thus for illustration, the character 100 is shown 15 located opposite the character Fancy, and enabling the shipper or fruit grower when he has a box containing 100 oranges of the "fancy" grade or quality to readily stamp the box with that mark by turning the body 20 until the character 100, which has previously been applied, to the ink pad in the ordinary manner, upon the box, and can thus print the same thereon, and similar marks 25 may be likewise applied to other closures as required. By providing a plurality of different characters the range of the improved device is greatly increased. By this means a shipper is not required to provide a plurality of separate stamps for each grade or 30 quality of goods, which are liable to become lost or broken, but can very quickly mark the different packages by simply turning the implement until the required character is next to the package to be marked. The flexible 35 strip, which is preferably endless, and slightly smaller than the circumference of the combined faces 11-12 of the body, will be sprung into the space between the ribs 15-16 when applied, and is thus held from 40 displacement by its own resiliency. The clamp plates 19 are then applied which prevent the strip from "creeping" around the body when in use, but will retain the strip with the thicker portions opposite the longer 45 flat faces.

The faces 13 enable the device to be supported above the shelf or other receptacle when not in use and protect the printing faces from injury.

50 The improved device is simple in construction, can be inexpensively manufactured and materially decreases the labor and expense of applying the denoting brands to packages.

What is claimed is:

60 1. A stamping device comprising a body

having an encompassing channel, an endless member of flexible material engaging in said channel and having printing characters thereon, clamping members bearing over the flexible member between the printing characters, and fastening devices operating through the clamping members. 65

2. A stamping device comprising a body having an encompassing channel formed into a plurality of relatively long flat faces and relatively short connecting flat faces, an endless member of flexible material engaging in said channel and having printing characters thereon opposite the longer flat faces, clamping members bearing over the flexible member opposite the short flat faces, and fastening devices operating through the clamping members. 70

3. A stamping device comprising a body having an encompassing channel formed into a plurality of relatively long flat faces and relatively short connecting flat faces, an endless member of flexible material engaging in said channel and having printing characters thereon opposite the longer flat faces and with the material of the endless member reduced opposite the shorter flat faces, clamping members bearing over the flexible member opposite the reduced portions, and fastening devices operating through the clamping members. 75

4. A stamping device comprising a body having its margin formed into a plurality of relatively long flat faces and relatively short connecting flat faces, an endless member of flexible material engaging said flat faces and having printing characters thereon opposite the longer flat faces and with the material of the endless member reduced opposite the shorter flat faces, clamping members bearing over the flexible member opposite the reduced portions, and fastening devices operating through the clamping members. 80

5. A stamping device comprising a body having its margin formed into a plurality of relatively long flat faces and relatively short connecting flat faces, an endless member of flexible material engaging said flat faces and having printing characters thereon opposite the longer flat faces, clamping members bearing over the flexible member opposite the shorter flat faces, and fastening devices operating through the clamping members. 85

In testimony whereof I affix my signature in presence of two witnesses.

DON J. HIGGINBOTHAM. [L. S.]
